UNITED STATES PATENT OFFICE.

OTTO G. PFEIFFER, OF SALT LAKE CITY, UTAH, ASSIGNOR TO UTAHNA DEVELOPMENT COMPANY, OF SALT LAKE CITY, UTAH, A CORPORATION OF UTAH.

WRINGER-GEARING FOR WASHING-MACHINES.

Specification of Letters Patent. Patented Dec. 30, 1913.

1,082,551.

Application filed December 27, 1911. Serial No. 668,186. Renewed May 2, 1913. Serial No. 765,133.

To all whom it may concern:

Be it known that I, Otto G. PFEIFFER, a citizen of the United States, and residing at Salt Lake City, in the county of Salt Lake and State of Utah, have invented certain new and useful Improvements in Wringer-Gearing for Washing-Machines, of which the following is a specification.

This invention relates to driving gearing, 10 and more particularly to wringer driving gearing for washing machines.

In operating a wringer by power it is desirable to drive the wringer in opposite directions, so that if the wringer should become clogged it can be reversed to permit the clothes to be taken out. In view of the fact that wringers are operated by inexperienced operators, the mechanism must be simple in its construction and operation, 20 and the controlling mechanism should be so arranged as to be easily manipulated.

One of the objects of this invention therefore is to construct a gearing in which the driven member, for instance the wringer shaft, can be driven at will in either direction, and in which this mechanism will consist of few parts so as to be simple in its construction and operation.

Another object is to provide manual controlling means for the gearing whereby the driven member may be controlled at will, and to construct this controlling means so as to be susceptible of operation by unskilled operators.

Further objects will appear from the detail description taken in connection with the accompanying drawings in which:

Figure 1 is a section on the line 1—1 Fig. 2, and Fig. 2 is a section on the line 2—2

Fig. 1.

Referring to the accompanying drawings, 10 designates a washing machine casing, and 11 a drum arranged to rotate therein in reverse directions and arranged to receive 45 clothes to be washed. The washing machine construction is fully shown and described in my application Serial No. 668,184 filed of even date herewith. The casing body is supported in a pair of end frames one of 50 which is shown at 12. These end frames are preferably malleable castings, while the casing body is of sheet metal. The end frame 12 has secured thereto or cast integral therewith a series of bearing lugs two of 55 which are shown at 13 and 14. A bracket

16 is bolted to the lugs and forms caps for the bearing lugs. A main drive shaft 17 is mounted in the bearing lugs and has mounted thereon a gear 18 meshing with a pinion on a motor shaft (not shown). The 60 shaft 17 forms the main drive shaft for driving a reversing mechanism for the drum 11, and for driving the wringer as herein-after described. The reversing mechanism and its relation with respect to the wringer 65 driving mechanism is fully shown and described in my application Serial No. 668,185 filed of even date herewith.

The wringer is generally designated by 60, and 61 designates the wringer shaft. 70 This shaft has mounted thereon a bevel gear 62 meshing with a bevel gear 63 on a cross shaft 64 mounted in bearing lugs 65 and 66 on the end frame 12. A bevel gear 67 is mounted on the lower end of the 75 shaft 64 and meshes with two bevel gears 68 loosely mounted upon the drive shaft 67. A jaw clutch member or sleeve 69 is splined upon the drive shaft 17 and is provided with jaws arranged to engage with coöperating 80 jaws upon the bevel gears 68. A clutch fork 70 is loosely mounted upon a shaft or rod 71 slidingly mounted in bearings in the lugs 13 and 14. This rod has rigidly mounted thereon two collars 72 and 73 respectively, 85 and springs 74 and 75 are mounted upon this rod, one between the collar 72 and the fork, and the other between the collar 73 and the fork. A vertical shaft 76 having an operating handle 77 is mounted for rotation in 90 bearing lugs 78 and 79 formed on the end frame 12. A disk 80 is mounted upon and connected to the lower end of the shaft 76 and is provided with a crank pin 81 connected by a pitman or link 82 with the collar 72. The disk is provided with a series of recesses 83 adapted to be engaged by a spring latch 84 mounted upon the end frame 12.

The connection of the drive shaft with 100 either of the gears 68 will cause the drive shaft to rotate the wringer shaft in reverse directions. The controlling means, described above, for causing such a connection of the gears, is so constructed that the 105 wringer shaft may be driven in one or another direction at the will of the operator. In the drawings, the mechanism is shown in neutral position at which time both gears 68 are loose on the shaft. If the han- 110

dle 77 and the shaft 76 are now rotated through a quarter of a revolution in one direction the wringer shaft will be driven in one direction, while if the handle and the shaft are turned from neutral position in the opposite direction, the direction of rotation of the wringer shaft will be reversed.

It will be noted that the controlling mechanism has two neutral positions, namely one 10 in which the crank pin 81 is in the position shown in Fig. 2, and another position in which the crank pin will be diametrically opposite. The shaft 76 can however be turned from either neutral position in any 15 desired direction to cause the wringer shaft to be driven in any desired direction. It will also be noted that when the shaft is in either of its clutch engaging positions, the clutch can be thrown to neutral position by 20 turning the shaft in either direction. This construction is of great advantage in washing machines, which are operated by unskilled operators, and in which the operator is liable to become excited (when the clothes 25 are tangled or caught) and forget in which way the handle should be turned to throw out the wringer shaft. With this construction however the operator is not required to remember this, since the shaft handle 30 can be moved in either direction to neutral position. The latch 84 will hold the shaft in any of its adjusted positions.

The handle 77 can be moved to its limit to throw in the clutch irrespective of the 35 position of the clutch member. This is due to the fact that the connection between the handle and the clutch member 69 is a yielding one (through the springs 74 and 75). Thus if the handle 77 is operated to throw 40 the clutch member 69 in while the shaft 17 is stationary and while the jaws of the clutch member are opposite the coöperating jaws on the bevel gears, the clutch member 69 will be moved until the jaws thereon engage the jaws on the bevel gear and further movement of the handle will serve to compress one of the springs 74 or 75. As soon 45 as the shaft 17 starts to revolve, or revolve sufficiently to align the jaws on the clutch member with the recesses on the bevel gear, the parts will snap together under the action 50 of the compressed spring.

It is obvious that various changes may be made in the details of construction without departing from this invention, and it is 55 therefore to be understood that this invention is not to be limited to the specific construction shown and described.

Having thus described the invention what 60 is claimed is:

1. In a machine of the class described, the combination with a drive shaft and a driven shaft, of bevel gears on one of said shafts, a bevel gear on the other of said shafts meshing with said first bevel gears, a clutch for

connecting either of said first bevel gears with their shaft, and means for shifting said clutch, said means being movable from an operative position in two directions to a neutral position to disconnect said first bevel gears from their shaft. 70

2. In a machine of the class described, the combination with a drive shaft and a driven shaft, of bevel gears on one of said shafts, a bevel gear on the other of said shafts meshing with said first bevel gears, a clutch for connecting either of said first bevel gears with their shaft, and a rotatable member for shifting said clutch, said member having two neutral positions and an intermediate operative position. 75

3. In a machine of the class described, the combination with a drive shaft and a driven shaft, of bevel gears on one of said shafts, a bevel gear on the other of said shafts meshing with said first bevel gears, a clutch for connecting either of said first bevel gears with their shaft, and a rotatable member for shifting said clutch to connect and disconnect said first gears to and from their shaft, said member having successive operative and neutral positions, and having a plurality of operative positions and a plurality of neutral positions. 85

4. In a machine of the class described, the combination with a drive shaft and a driven shaft, of bevel gears on one of said shafts, a bevel gear on the other of said shafts meshing with said first bevel gears, a clutch for connecting either of said first bevel gears with their shaft, a rotatable crank disk connected to shift said clutch, said crank disk having a plurality of recesses, and a detent engaging said recesses. 95

5. In a machine of the class described, the combination with a drive shaft and a driven shaft, of bevel gears on one of said shafts, a bevel gear on the other of said shafts meshing with said first bevel gears, a clutch for connecting either of said first bevel gears with their shaft, a rotatable controlling shaft, and a crank on said shaft having a yielding connection with said clutch to shift the same as said controlling shaft is rotated. 105

6. In a machine of the class described, the combination with a drive shaft and a driven shaft, of bevel gears on one of said shafts, a bevel gear on the other of said shafts meshing with said first bevel gears, a clutch for connecting either of said first bevel gears with their shaft, a sliding rod, a fork thereon engaging said clutch, a rotatable controlling shaft, and a crank on said shaft connected to said sliding rod. 110

7. In a machine of the class described, the combination with a drive shaft and a driven shaft, of bevel gears on one of said shafts, a bevel gear on the other of said shafts meshing with said first bevel gears, a clutch 120

for connecting either of said first bevel gears with their shaft, a sliding rod, a fork thereon engaging said clutch, a spring between said rod and said fork, a rotatable controlling shaft, and a crank on said shaft connected to said sliding rod.

8. Wringer driving gearing for washing machines, comprising a drive shaft, a wringer operating driven shaft, a bevel gear 10 on one of said shafts, a pair of bevel gears on the other of said shafts arranged to mesh with the first gear, means for controlling said gears, constructed and arranged to cause the drive shaft to drive said driven 15 shaft, in one direction through said first gear and one of said pair of gears, and in

the opposite direction through said first gear and the other of said pair of gears, and a rotatable manually operable member connected to shift said controlling means, said member having two operative driving positions corresponding to the two directions of drive, and said member being movable from either operative driving position in either direction to a neutral position to disconnect 20 25 said shafts.

In testimony whereof I affix my signature in presence of two witnesses.

OTTO G. PFEIFFER.
